Attorney.

UNITED STATES PATENT OFFICE.

LOUIS JOSEPH TURCOTTE, OF MONTREAL, QUEBEC, CANADA.

WINDOW CONSTRUCTION.

Application filed October 10, 1927. Serial No. 225,247.

The invention relates to window construction, as described in the present specification and illustrated in the accompanying drawings that form part of the same.

- 5 The invention consists essentially of the novel features of construction pointed out in the claim for novelty following a description containing an explanation in detail of an acceptable form of the invention.
- 10 The objects of the invention are to avoid dangers incident to the cleaning of windows; to make reversible windows adaptable to the colder climates by closing up joints and thereby stopping the penetration of the cold air;
- 15 to insure reliable fastening in the sash guides; and generally to provide an efficient and economical reversible window.

In the drawings, Figure 1 is a perspective view of the window showing the sashes in 20 their normal positions.

Figure 2 is a perspective view of the window showing the sashes reversed for cleaning purposes.

Figure 3 is a cross sectional view on the line 25 3—3 in Figure 2.

Figure 4 is a detail of the latch in the removable strip.

Figure 5 is a perspective detail of a sash and sash runner.

30 Figure 6 is an enlarged detail showing an inserted weather strip.

Like numerals of reference indicate corresponding parts in the various figures.

Referring to the drawings, the window 35 frame 10 has the inner and outer longitudinal grooves 11 and 12 at one side, the grooves being partially closed in from either side by the metal flanges 13, 13 and 14, 14, which are secured by means of screws to the inner sides of 40 the walls 16 of the side walls or strips of the grooves 11 and 12.

The upper and lower window sashes 35 and 36 respectively are slidable in the longitudinal grooves 11 and 12 and adapted to be 45 pulled up and down and held by means of the sash cables 18 and 19 trained over the pulleys 20 and 21 leading into the weight box 22.

The window sashes are carried on the one side by the sliding brackets 23 and 24 having 50 the runners 25 and 26 sliding in the longitudinal grooves 11 and 12 respectively and retained therein by the flanges 13, 13 and 14, 14, said brackets 23 and 24 being metal bound at their inner sides as shown by the metal strip 55 coverings 27 and 28 respectively.

The sashes 35 and 36 are recessed at 30 and 31 respectively and fit into the corresponding recesses 32 and 33 in the sliding brackets 23 and 24 thereby forming effective seats for weather strips as shown in the detail in Figure 6, and indicated by the numeral 17, and which is a very salient feature in this invention, for most of the trouble in connection with reversible windows has been caused by their inefficiencies during the winter season. 60 The sashes 35 and 36 are secured to the brackets 23 and 24 by the hinges 34, therefore these sashes will swing freely inwardly making it possible to wash the outsides of the window panes from the interior of the 70 room and thus avoid the necessity of going outside with its consequent dangers.

The free ends of the window sashes 35 and 36 are normally retained in the outer and inner sliding grooves 38 and 39 respectively. 75 The wall of the outer groove is cut away to form the removable sash strip 40 and this removable sash strip 40 has a pin 41 extending from its lower end and inserted in the sill 42 within the hole 43 and towards its upper end the said strip 40 is held to the frame by the spring latch 44 which snaps into the catch 45 of the frame, thus retaining the sash in its place under ordinary conditions, the removable strip 40 is recessed in the frame 10 80 for its complete length, the recess 46 in the frame containing the catch 45 and extends for the whole length of the strip 40 below the permanent strip 47 of which the strip 40 forms a continuation of the grooved wall. 90

The inside wall of the inner sash groove is also divided into permanent and hinged sash strips 48 and 49 respectively, the removable strip 49 being secured to the window frame 10 by the hinges 50 and 51 and meeting the strip 48 in the bevelled joint 52. The strip 49 closes in on the frame 10 against the sash 36 and inside the aligning snap fastener 53 is secured to the strip 49 and to the window frame respectively in regard to its two 95 members the inner member having an aligning pin 54 to insure a continuance of the strip 49 of its close fit to the window sash 36.

In the operation of this window the lower sash fits into the sill, that is to say, closes 100 down behind the inside ledge, which is customary construction, but it means that it has to be lifted slightly to escape the ledge of the sill, the strip 49 is then swung on its hinges which leaves the sash 36 free to be 110

opened inwardly for cleaning purposes. The strip 40 is then removed by pressing on the spring latch and the sash 35 drawn downwardly until it escapes the lower end of the permanent section of the middle wall separating the sash grooves. This upper sash then can be opened for cleaning purposes the same as the lower sash.

It really must be emphasized herein the 10 important construction in this invention tending towards weather tightness, in other words, wherever these reversible windows have been installed in public and other buildings the cold weather has always proved a 15 bar to their success and scarcely any attention has been paid to the making of good tight joints as has been carefully thought out in this construction in respect to the various constructional parts.

20 What I claim is:—
A window structure comprising a window

frame having sash grooves in opposite sides and metal strips secured to the frame partially closing in the grooves and forming guides, 25 a sash having a vertical rabbet at one side, a wooden bracket forming a sash support and having metal facing strips forming vertical binding pieces running on said metal strips in the window frame and having a rabbet 30 registering with the vertical rabbet in said sash and completing a rabbet joint in the closed position and converging at the inner side to a neck, a runner forming a part of said wooden bracket and sliding in one of the window grooves and a hinged strip section 35 having fasteners thereon locking the sash frame in the other of said window grooves.

Signed at Montreal, Canada, this 29th day of September, 1927.

LOUIS JOSEPH TURCOTTE.
